ENVELOPE MACHINE

Ernst C. Sauerman, Chicago, Ill.

Application April 11, 1936, Serial No. 73,843

3 Claims. (Cl. 93—73)

This invention relates to machines for producing envelopes of the type having bottom and side or end flaps, some or all of which are adhesively secured together to complete the envelope 5 pocket. More especially the present invention is directed to improvements in or attachments for such machines for printing on the back side of the envelopes while the envelope blank is passing through the machine, during the process 10 of formation.

For certain commercial uses various types and sizes of envelopes are desired, and for certain purposes it is desired that the back side of the envelopes be provided with printed matter, such as 15 instructions for opening, notice for postal inspection, or other matter.

Generally such printed matter and information has heretofore been applied to the backs of the envelopes by a separate operation on a printing press, after completion of the envelope on an envelope making machine. This practice has often been found unsatisfactory because of time 20 consumption and increase in cost of labor, and primarily because the printing press when so used is not available for use in printing the general run of work, which, on the whole, is much 25 more profitable than the operation of printing on the back of envelopes. Manifestly such delay in production of higher paying work materially 30 reduces the margin of profit in handling higher grade printing jobs.

There have been several attempts to solve the foregoing problem. For example, in the Oles Patent No. 1,879,990 there is disclosed a construction and arrangement for printing on one of the 35 end flaps of the envelope. The construction disclosed in this patent, however, has very severe limitations in that the printed matter may be applied only to one of the end flaps, and which 40 flap cannot be fully and properly adhesively secured to the other flap or flaps for completing the envelope pocket, due to the fact that the printing and adhesive applying mechanism are carried on the same shaft and operate simul- 45 taneously on the envelope blank. Moreover, Oles' arrangement for printing and applying adhesive to the respective end flaps is such that there is a great possibility of obtaining imperfect and relatively light or heavy printing due to pos- 50 sible variation in consistency of the adhesive which will tend to either hold the printing plate too far from the surface of the envelope, or permit the plate to move too close to the surface of the envelope.

The present invention is directed to a novel

construction and arrangement of printing means by virtue of which either or both end flaps and/or bottom flap may be printed while the envelope blank is passing through the machine, during process of formation. The printing mechanism is 5 constructed and arranged for performing the printing operation after the end flaps and bottom flap have been folded and adhesively secured together to complete the envelope pocket, thus making it possible to properly secure the bottom 10 flap to either or both of the end flaps of the envelope since this operation precedes the printing operation. Because the printing operation is totally independent of the folding operation and the adhesive securing of the flaps there is no 15 possibility of the adhesive in any way affecting the character or quality of the printing on the envelope. This invention also contemplates the provision of a novel construction and arrangement whereby the printing mechanism is ren- 20 dered inoperative in response to the non-feed of an envelope blank.

Other advantages and objects of the present invention will appear in the following description, taken in connection with the accompanying 25 drawings in which:

Fig. 1 is a side elevation of the rearward portion of an envelope making machine, embodying the present invention;

Fig. 2 is a plan view of the rearward portion 30 of the machine;

Fig. 3 is a transverse section through the machine taken as indicated at line 3—3 on Fig. 1;

Fig. 4 is a section taken as indicated at line 4—4 on Fig. 3;

Fig. 5 is a fragmentary sectional view taken at line 5—5 on Fig. 1 showing the cam means for assisting in controlling the printing mechanism, in response to non-feed of an envelope blank;

Fig. 6 is a view similar to Fig. 3 showing the printing mechanism disposed in inoperative position resulting from the non-feed of an envelope blank;

Fig. 7 is a fragmentary section taken adjacent 45 one end of the shaft carrying the printing mechanism, including a cam and cooperating means by virtue of which the printing mechanism is shifted to and from operative position;

Fig. 8 is a sectional view similar to Fig. 7 showing the parts adjusted in position corresponding to the disposition of printing mechanism in inoperative position, as seen in Fig. 6;

Fig. 9 is a fragmentary section showing the 50 feeler finger, disposed in the path of travel of 55

envelope blank and which responds to the non-feed of an envelope blank, and taken as indicated at line 9—9 on Fig. 2;

Fig. 10 is a fragmentary section of the interlocking means controlled by the feeler finger;

Fig. 11 is a section similar to Fig. 10 showing the interlocking means at position corresponding to non-feed of an envelope blank, and taken as indicated at line 11—11 of Fig. 2;

10 Fig. 12 is a transverse section taken as indicated at line 12—12 on Fig. 3, showing the cam control at a position of adjustment at which the printing mechanism is disposed in operative position;

15 Fig. 13 is a view similar to Fig. 12 showing the cam control means in a position at which the printing means is disposed in inoperative position;

20 Fig. 14 is a plan view of the rearward side of an envelope, having its flaps provided with printed matter and produced on a machine embodying this invention.

The present invention is applicable to envelope making machines of the type for producing "letter style" and/or "catalog style" envelopes. By

25 "letter style" envelope is meant envelopes of the type generally used for correspondence and the like, and is characterized by having its end flaps folded over against the body panel with the

30 bottom flap adhesively secured to one or both end flaps for completing the envelope pocket. The term "catalog style" envelope is used in the generic sense, and is intended to include envelopes known as "open end", "open side", "coupon"

35 and other types adapted to be used for advertising matter, data, containers, etc. and is characterized by having its end flaps adhesively secured together, and having the bottom flap adhesively secured to one or both of the end flaps.

40 For purpose of illustration I have selected an envelope making machine of the type for producing "letter style" envelopes as indicated at 1, in Fig. 14 which includes end flaps 2 and 3 and top and bottom flaps 4 and 5 respectively. Manifestly envelopes of this type may be produced so that the bottom flap is adhesively secured to either one or both of the end flaps, depending upon the character, or use of the envelope desired.

45 For convenience the drawings disclose only the rearward portion of a commercial form of envelope making machine, embodying the present invention, and in which the envelope blanks are fed therethrough in the direction indicated by the arrow in Figs. 1 and 2. It is to be understood that the envelope blank prior to passing through the portion of the machine illustrated, is first creased to form lines of fold for end, top and bottom flaps. Then the end flaps are folded over the body portion of the blank and are fed preferably centrally through the machine over a bed plate 10, rigidly secured to spaced apart standards or side frames 11. The blank with the end flaps folded thereover is then fed to a pair of positively driven friction rollers 13 which cooperate with a driven roller therebeneath (not shown) for advancing the blank forwardly so that the obliquely disposed adhesive applying blades indicated at 14, carried on the rotary shaft 15, engage and apply adhesive to the two forwardmost diagonally extending edges of the folded over end flaps 2 and 3. Manifestly if desired only one of the adhesive applying blades may be employed, and the shape and location of such blade will naturally depend upon the shape and overlapping arrangement of the flaps of the envelope blank.

5 The friction rollers 13 as well as the adhesive applying blades 14, are positively driven by suitable gearing from a main drive shaft, as seen in Fig. 2 of the drawings, so as to continue to advance the blanks through the machine in a predetermined spaced apart relation. The blanks are advanced from the adhesive applying blades by reason of their contact with the resilient surface of a roller, disposed below said blades to a folding mechanism indicated generally at 18. 10 This folding mechanism is well understood in the art, and is constructed so that the bottom or forwardmost flap 5, of the blank is deflected upwardly, and when it arrives at a predetermined position a pair of timed spaced-apart tucker 15 fingers 20 carried on rock shaft 21 engage the blanks, substantially at the score line defining the bottom flap, so that as these tucker fingers move downwardly the blank is fed between a pair of superimposed rolls 23, as seen in Fig. 4, 20 for folding the bottom flap 5 onto the adhesively coated surfaces of the side flaps 2 and 3 for completing the envelope pocket. The rolls 23 feed the partially formed envelope forwardly over the bed plate 10, into engagement with a 25 pair of spaced apart positively driven friction rollers 25 carried on a shaft 26. Cooperating with said rollers 25 and disposed therebeneath as seen in Fig. 4 is a positively driven roller 29, and said rollers 25 and 29 feed the partially folded 30 envelope through another folding device (not shown) for folding the top or sealing flap 4, down on the end and bottom flaps, for completing the envelope.

The present invention contemplates the provision of means for printing information or data on either or both of the folded end flaps 2 and 3 and/or the bottom flap 5 of the envelope, while the blank is passing through the machine, and this operation is performed after the bottom flap 40 5 is folded against the end flaps 2 and 3 so that the printing operation is totally independent of the adhesive applying mechanism or the mechanism for folding the flaps of the envelope blank.

45 The printing means disclosed in the drawings includes supporting elements 32, carried on the shaft 26 and on each element there is secured printing plate members indicated at 33. Said supporting members are positioned along said shaft 26 so that the printing plates 33, are brought into registration with and print the folded end flaps 2 and 3 as indicated in Fig. 14. Desirably the roller 29 located immediately below the shaft 26 as seen in Figs. 3 and 4 is provided with a resilient or hard surface to serve as an impression 55 roll for the printing plates. As is apparent, each of the members 32 are formed as clamp members and are each provided with clamping screws 34, which permits quick and easy detachable securing thereof along said shaft 26, and therefore 60 said members 32 with their respective printing plates may be quickly and easily removed or replaced or adjusted along on said shaft, and if desired even an additional member 33 and printing plate may be employed for printing on the bottom 65 flap 5 of said envelope blank. It will also be recognized that these printing members need not necessarily be located in axial alinement, but may be disposed in angular relation to each other so that the printing on said flaps is disposed in offset 70 relation. The shaft 26 and impression roll 29 are interconnected by suitable gearing indicated at 35 so that the peripheral speed of the surface of said rollers 25 and 29 will be the same for feeding the envelope blank therebetween while the print- 75

ing operation is being performed. These rollers as well as rollers 23 are all driven from the same power source as the other device previously described so as to feed the envelope blanks in timed spaced-apart relation to the other mechanisms of the machine.

The printing plates 33 are adapted to receive ink from inking roller 31 which in turn is contacted by transfer roller 38. Roller 40, the periphery of which passes through a body of ink carried in a trough indicated generally at 41, picks up a suitable quantity of ink from the trough and transmits it to the surface of roller 42 which oscillates back and forth into peripheral contact with the respective rollers 38 and 40, while roller 38 is shifted axially back and forth, while in contact with the ink applying roller 37, for evenly distributing a uniform coating of ink on the surface of said roller in a manner well understood in the art. The mechanism for causing oscillation of rollers 38 and 42 is well understood in the art, and is therefore illustrated in outline in the drawings, and a detailed description thereof is believed unnecessary, other than to state that said rollers are also driven in timed relation to the rotation of the printing plates 33 carried on the shaft 26 by a chain drive as indicated generally at 44.

Envelope blanks as they are fed through the machine of this type initially are mechanically spaced apart a desired predetermined distance, and it is possible that said mechanism may occasionally become inoperative in that it may occasionally fail to feed a blank, thus interrupting a continuous series of spaced apart blanks. Furthermore, during the passage of the envelope blank to the various mechanisms of such a machine, it sometimes happens that a blank must for some reason or other be removed so as to prevent jamming of the machine, to avoid upsetting the timed spaced-apart relationship of other oncoming envelope blanks. Therefore, in order to avoid functioning of certain devices on the machine, there is provided means which is responsive to the non-feed of a blank at certain portions in the machine, and in the present instance this means includes a feeler finger indicated at 50 which is registered with an aperture 10a in the bed plate located forwardly of the adhesive applying mechanism. This feeler finger is of bifurcated formation and straddles a roller member 51 as seen in Fig. 2 of the drawings, and with which roller cooperates a superimposed roller, and between which rollers the envelope blanks are fed in a forward direction. Feeler fingers of this character have heretofore been employed as above mentioned for rendering various devices of the machine inoperative in response to the non-feed of an envelope blank, and in the present instance it may be understood that the feeler finger is connected to mechanism for rendering the adhesive applying mechanism inoperative in response to non-feed of an envelope blank over said finger. I contemplate employing this same mechanism controlled by the feeler finger 50, for rendering my printing mechanism inoperative in response to the non-feed of an envelope blank, as will presently be described.

The feeler finger 50 is mounted on a transversely extending rock shaft 52 journaled in the side frames or standards 11, and connected to one end of said rock shaft is a control lever 53. It may be understood that the feeler finger, rock shaft and control lever 53 are so constructed and

arranged that they are relatively sensitive in that they are normally held in inoperative position by passage of an envelope blank over said finger, as seen in Fig. 9, and when a blank does not pass thereover at the proper timed interval the feeler finger swings upwardly to the position indicated in dotted lines in Fig. 9, thereby rocking the control lever 53 in a downward direction. The outer end of said lever 53 is provided with a transversely extending portion 53a adapted for interlocking cooperative engagement with a lever arm 55 rigidly carried on a vertically extending rock shaft 56 journalled in bearings 11b of the adjacent side frame member 11 as seen in Fig. 1. The end of said lever 55 adjacent the interlocking end 15 of the lever 53a is provided with an upstanding projection 55a having an aperture 55b through which the extreme end of portion 53a of lever 53, is adapted to be projected when the finger 50 is actuated by reason of the fact that no envelope blank has been fed thereover in a proper timed interval. The upper portion of said block on the side adjacent said portion 53a is provided with a V-shaped recess 55c adapted to be engaged by the V-shaped terminal portion 53b of said lever 25 portion 53a for interlocking engagement therewith while envelope blanks are continuously passing through the machine in proper predetermined spaced apart relation. Connected to the lower end of the vertical rock shaft 56 is a lever 30 arm 59 the outer end of which is provided with a roller 60 adapted for engagement with the face of a cam member 61 mounted on a transversely extending shaft 62 journalled in the side frames 11, and which shaft is in turn driven by suitable 35 gearing from the main drive shaft of the machine, in timed relation to the feeding devices on the machine, so that said cam makes a complete revolution corresponding to the interval of time lapsing between adjacent envelope blanks passing a predetermined point in the machine. Said cam is provided with a raised portion 61a which 40 encounters the roller 60 at each revolution of the shaft 62 so as to rock the lever arm 59 in counterclockwise direction with respect to the view seen 45 in Fig. 5 thereby rocking the vertically disposed shaft 56 which in turn rocks the lever 55 in the same direction as the lever 59. The levers 55 and 59 are maintained at their innermost position so that the roller 60 is yieldingly maintained in 50 contact with the surface of the cam 61 by a coil spring 63 connected to an extension of the lever 55 and to the opposite frame member 11. Thus any rocking movement of the shaft 56 by encounter of the roller 60 with the high point 61a 55 of the cam takes place in opposition to the reaction of said spring 63. Rigidly connected to the lever arm 55 is a rearwardly extending lever arm 65 the opposite end of which is connected by a tension spring 67 to the end of the transversely 60 movable and substantially horizontally disposed stud or pin 69 carried in a socket 70 mounted in the frame 11. Said pin 69 is provided with an enlarged portion 69a for guiding the pin when it is moved in axial direction in the socket 70. Circumscribing said pin and reacting against a shoulder 70a of the socket and the end of the enlarged portion 69a is a coil spring 71 which tends to oppose retraction of the pin. Mounted on the inner end of the pin 69 is a roller 73 which 65 normally, when envelope blanks are passing in continuous spaced apart relation through the machine, is disposed in the position seen in Fig. 7 in registration with the hub portion of a cam 76 mounted adjacent one end of the shaft 26. Said 75

cam is provided with a flange 76a which normally maintains the roller 73 in such position while envelope blanks are continuously passing through the machine. Said flange is formed with a cut 5 away portion or notch 76b as seen in Fig. 12 so that when disposed in registration with the roller 73 withdrawal of the pin 69 in outward direction will cause said roller to pass through said notch into registration with the cam surface 76c, as 10 seen in Fig. 8 of the drawings. Thus due to the contour of the cam surface 76c, continued rotation of shaft 26 will cause the adjacent end of said shaft to be raised, thus lifting the printing devices 32, 33, and said rollers 25 out of 15 operative relation to the impression roll 29 to the position seen in Fig. 6. This condition occurs, however, only when there is a break in the continuous feed of envelope blanks in proper spaced apart relation through the machine.

20 To permit such movement of the shaft 26 carrying the printing devices and said rollers 25, the ends of said shaft are carried in bearing blocks 79 mounted in guide-ways in the side frames 11 and are normally urged downward by 25 coil springs 80. Suitable tensioning devices indicated generally at 81 are mounted on the respective frames and permit adjustment of the tension on said springs 80 to a desired degree for holding the shaft 26 in proper position. Such 30 construction manifestly permits movement of one end of the shaft in an upward direction while the opposite end acts more or less as a fulcrum.

When envelope blanks are continuously passing through the machine in proper spaced apart 35 relation the feeler finger 50 is maintained depressed as seen in Fig. 9 and each time cam 61 rotates, which corresponds to the timed interval between adjacent blanks, the high portion 61a of said cam rocks shaft 56 so that the block portion 55a of lever 55 is moved out of contact with the interlocking end 53b of the lever 53, and as 40 soon as the high point 61a on the cam is passed the lever 55 returns under the influence of the spring 63, returning the block 55 for interlocking engagement with the end 53b of lever 53, as seen 45 in Fig. 10. As long as the envelope blanks are passing in a continuous series the portion 53a of the lever is maintained substantially at the position indicated in Fig. 10, and it may be understood that the action by the high point 61a of the 50 cam 61 takes place just prior to the passage of an envelope blank over the feeler finger 50. As will be apparent, this permits the lever 55 to be rocked outwardly so that its groove 55c will be moved 55 out of contact with the V-shaped terminal portion 53b of the lever 53 thus allowing said lever 53 freedom of action in the event no envelope blank registers with the feeler finger 50 at the 60 timed interval corresponding to the spaced apart relationship of the blanks. Moreover, as long as the envelope blanks are passing through the machine in a continuous series, the printing mechanism continues to function so that the printing plate successively registers with the partially 65 completed envelopes at the proper timed intervals.

In the event that a series of envelope blanks as fed through the machine is broken for any reason whatsoever, or for example upon completion of a 70 run of envelope blanks through the machine, the feeler finger 50 is then rendered free to function because at the time that no envelope blank passes over finger 50, and because the cam 61 has just previously rocked lever 55 outwardly releasing the interlocking portion 53a of lever 53, the finger

50 may move upwardly to the dotted position seen in Fig. 9. When said finger swings to such position the interlocking portion 53a of the lever 53 swings downwardly to the position seen in Fig. 11 so that the terminal portion 53b thereof registers 5 with the aperture 55b of the block 55a which forms a part of the lever 55, and as said lever 55 returns, after passage of the high point 61a of said cam, by the influence of the spring 63, it telescopes over the end of the interlocking portion 10 53a of the lever 53, as seen in Fig. 11. Such movement of the lever 55 causes the lever arm 65 to swing outwardly tensioning spring 67 and causing roller 73 to hug the flange 76a of the cam 76 as seen in Fig. 7 of the drawings. Now 15 because there is a period of time in travel of envelope blanks from the feeler finger 50 to the printing mechanism the means for rendering the printing mechanism inoperative must allow for travel of the previous blank that has passed 20 the feeler finger, to be printed, while insuring that the printing mechanism is rendered inoperative at the time which would correspond to the registration of an envelope blank when there is a gap in the continuous feed of the blanks. 25 Therefore, it is to be understood that when the feeler finger is actuated by reason of the fact that there is an absence of an envelope blank at the time corresponding to the proper interval of spaced apart relationship of the blanks, the 30 open portion 76b of the cam 76 is in the position seen in Fig. 12 so that although the lever 65 has been swung in outward direction tensioning the spring 67 the roller 73 cannot engage the operative surface of the cam until the notch 35 76 registers therewith, which will take place upon rotation of shaft 26 a half revolution. When said notch 76b registers with the roller 73 the tension in spring 67 acting on the pin 69 moves the roller 73 into registration with the 40 cam surface 76c thereby tensioning the spring 71. During said half revolution of the shaft 26 prior to the time that the roller 73 is moved into operative engagement with the cam surface 76c, it is to be understood that the last envelope blank 45 before the gap, or at the end of the series, has been fed over the bed plate and printed in the usual manner. Manifestly as the shaft 26 continues to rotate with the roller 73 engaging the cam surface 76c the adjacent end of shaft 26 50 and bearing 79 will be moved upwardly against the reaction of the spring 80 thereby lifting the printing devices 32, 33, and the said rollers 25 out of cooperative relationship to the impression roll 29 as seen in Fig. 6.

55 As long as no envelopes pass through the machine the printing mechanism will be maintained raised in inoperative position. The rock shaft 56, however, will continue to operate as long as cam 61 rotates thus transmitting motion to the 60 lever 65 and which because of its spring connection with the pin 69 releases the tension on said pin at periodic intervals corresponding to the rotation of the cam 61. Just as soon as the high spot 61a of the cam passes roller 60, the 65 shaft 56 is returned by the spring 63 so that roller 73 will be maintained in the position seen in Fig. 8 for rendering the printing mechanism inoperative. When envelopes are again fed through the machine, or when the next envelope 70 after a break in a series passes over the finger 50, said finger is depressed and as the lever 55 has been already swung outwardly, prior to registration of the block over finger 50, due to the action of the cam 61 rocking the shaft 56 in timed rela- 75

tion, the block 55a is withdrawn so that said feeler finger is free for responsive action to the passage of an envelope blank thereover. Therefore, as the envelope blank passes said feeler finger and depresses same it swings the portion 53a of the lever 53 in an upward direction to the position seen in Fig. 10 so that upon return movement of the lever 55 by the spring 63 the notched portion 55c engages the V-shaped terminal portion 53b of the lever 53 and holds said lever 53 from temporary vertical movement, and which in turn blocks complete inward movement of the lever 55. Such blocking movement releases the tension on spring 67 at the end of the lever 65 15 as seen in Fig. 8 so that said roller 73 under the influence of the tension of the spring 71 is urged against the flange 16a tending to return the roller to its normal free position. However said roller remains confined in cooperative engagement with the cam surface 16c corresponding to an interval representing one-half of a revolution of the shaft 26 which corresponds to the period of time for feeding of an envelope blank from the feeler finger to the printing mechanism. 20 Thus, after the cam 16 has been rotated to permit registration of its notch 16b with the roller 73 said roller together with its pin 69 is projected inwardly by the spring 71 to the position seen in Fig. 7. The shaft 26 in such position disposes the 25 printing devices and feed rollers 25 in proper cooperative relation to the impression roll 29 for printing on the partially completed envelope blanks as they register therewith.

Although I have shown and described my invention in connection with a certain type of envelope making machine, manifestly it is adaptable by a slight alteration or modification to other types of envelope making machines, without departing from the spirit and scope of this 30 invention. I do not, therefore, wish to be understood as limiting my invention to the specific form herein shown and described, except as indicated in the appended claims.

I claim as my invention:

45 1. In a method of producing envelopes containing printed matter on the back side thereof on an envelope making machine, wherein blanks

are fed forwardly in seriatim in predetermined spaced apart relation, said blanks being creased to provide lines of fold, and wherein the end flaps are folded upon the body of the blank, the improvement which comprises folding and adhesively securing the bottom flap to one or both of the end flaps to complete the envelope pocket, and then feeding said envelopes, in timed relation with the folding and adhesively uniting operations, for printing on one or more of said 10 folded flaps. 5

2. In an envelope making machine comprising means for feeding envelope blanks in timed spaced apart relation, means for creasing said blanks to form lines of fold for end and bottom flaps, and means for folding said end flaps, the combination of means for adhesively securing the bottom flap to one or both of said end flaps to complete the envelope pocket, means including a rotatable shaft, and two axially spaced apart 15 rollers carried on the shaft and positioned to frictionally engage the lateral edges of the partially folded blanks for feeding them forwardly, and means on said shaft for printing on one or more of said flaps, subsequent to the adhesive 20 securing of the bottom flap, all of said means for performing said operations on the blanks being operable in timed relation to each other. 25

3. In an envelope making machine comprising means for feeding envelope blanks in timed spaced apart relation, means for creasing said blanks to form lines of fold for end and bottom flaps, and means for folding said end flaps, the combination of means for adhesively securing the bottom flap to one or both of said end flaps 30 to complete the envelope pocket, means for printing on one or more of said folded flaps, subsequent to the adhesive securing of the bottom flap, and means responsive to the non-feed of an envelope blank for temporarily rendering said 35 printing means inoperative, said last mentioned means including delayed action connections for permitting completion of the printing operation on an aligned envelope, before rendering said printing means inoperative. 40 45

ERNST C. SAUERMAN.
